[57] CLAIM

The ornamental design for shower door handle unit, as
shown.

DESCRIPTION

FIG. 1 is an outer side elevational view of a shower
door handle unit showing our new design;

FIG. 2 is an inner side elevational view thereof;

FIG. 3 is a bottom plan view thereof, the top being a
mirror image;

FIG. 4 is a front elevation view of the left element
shown separately for clarity of illustration;

FIG. 5 is a front elevation view of the right element also
shown separately for clarity of illustration;

FIG. 6 is an exploded left perspective view thereof;

FIG. 7 is an exploded right perspective view thereof;
and,

FIG. 8 is a left perspective view thereof, the broken line
showing of a portion of a shower door being for illustra-
tive purposes only.
